(57) **CLAIM**

The ornamental design for a churro-shaped pet treat, as shown and described.

DESCRIPTION

FIG. 1 is a front, top and left side perspective view of a first embodiment of a churro-shaped pet treat according to the new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front, top and left side perspective view of a second embodiment of a churro-shaped pet treat according to the new design;

FIG. 9 is left side elevation view thereof;

FIG. 10 is a right side elevation view thereof;

FIG. 11 is a front elevation view thereof;

FIG. 12 is a rear elevation view thereof;

FIG. 13 is a top plan view thereof; and,

FIG. 14 is bottom plan view thereof.

The break lines shown in the middle portion of the churro-shaped pet treat in FIGS. 8-10 and 13-14 indicate that the appearance of any portion of the article between the break lines forms no part of the claimed design.
